UNITED STATES PATENT OFFICE.

MINNIS HEADEN, OF CHRISTIANSBURG, VIRGINIA, ASSIGNOR OF SEVEN-EIGHTHS TO D. W. FRIZZELL, OF SAME PLACE.

OLIVER.

SPECIFICATION forming part of Letters Patent No. 325,342, dated September 1, 1885.

Application filed July 9, 1885. (No model.)

To all whom it may concern:

Be it known that I, MINNIS HEADEN, a citizen of the United States, residing at Christiansburg, in the county of Montgomery and 5 State of Virginia, have invented a new and useful Improvement in Olivers, of which the following is a specification, reference being had to the accompanying drawings.

My invention relates to olivers or that class 10 of devices to operate a power-hammer, the latter being lowered to strike an object and raised from the same, when the stroke is finished, for another stroke.

The object of the invention is to provide a 15 device of this character which shall be simple in its construction, inexpensive to manufacture, not likely to get out of order, and one that may be readily and easily operated with but little exertion.

With this end in view the said invention 20 consists in the peculiar construction and combination of parts, as hereinafter set forth, and particularly pointed out in the claims.

In the drawings, Figure 1 is perspective 25 view of my improvement. Fig. 2 is an end elevation showing the positions occupied by the parts when the hammer is lowered, and Fig. 3 is a detail vertical sectional view showing the arrangement of the springs for returning the frame for raising the hammer to its 30 normal position.

In the accompanying drawings, in which like letters of reference indicate corresponding parts in all the figures, A A' represent base-beams, which are connected by the cross or tie 35 beams a a'.

Extending upwardly from the beams A A', near the forward ends thereof, are uprights or standards B, which are braced and supported 40 in a vertical position by the bars b, which are set at an incline, as shown. The uprights or standards B are connected near their upper ends by a bar, c, which serves to hold the beams together against spreading, and is also adapted 45 to limit the upward movement of the hammer, as will be more fully described.

Journaled in openings of the uprights or standards B is a shaft, C, which shaft is located about midway the upper and lower ends 50 of the said uprights or standards B.

Secured to the shaft C midway between the uprights or standards B is an arm or handle, D, on the outer end of which is secured a hammer of any ordinary or well-known construction.

E represents a frame, which is located at the rear ends of the beams A A'. This frame E consists of the vertical bars F, which are connected with the tie-beam a by spring-rods c d, the lower ends of which rods are embedded in 60 the tie-beam a, while their upper ends may be secured to the vertical bars F in any suitable manner. The vertical bars F are connected at their upper ends by a bar, G, to which are secured the ends of ropes or chains 65 e, which are wrapped one or more times around the shaft C and have their ends secured thereto. By this arrangement it will be seen that the spring-actuated frame is connected with the shaft C, and that if said frame should be 70 moved forwardly the hammer would drop by its own weight, and that when the frame was released the hammer would be returned to a raised position by the action of the spring-rods c d.

Swiveled to the tie-beam a or at any other suitable point upon the frame is a foot-lever, H, near the outer end of which is secured one end of a rope or chain, f, the other end of which is wrapped upon the shaft C and secured thereto.

The operation is as follows: The object to be struck or hammered is placed in such a position that when the hammer is lowered it will strike the same. The foot-lever H is depressed at its outer end by the foot or otherwise. This action causes the shaft C to be partially turned, inasmuch as the connecting rope or chain is wound around the same. As the shaft C is turned the hammer is lowered 90 upon the object, the spring-actuated frame being drawn forward by the connecting ropes or chains, which wind upon the shaft C. As soon as power is removed from the foot-lever H the spring-actuated frame, in attempting to 95 resume a vertical position by the action of the spring-rods c d, unwinds the ropes or chains from the shaft C and partially turns the same backward, which movement causes the hammer to be raised, the bar c preventing the 100

backward movement of the hammer further than a vertical line.

While I have described my improved motor as particularly adapted for hammers, it will be seen that it is applicable to other uses—for instance, the motor may be applied to churning, washing-machines, and the like, by a simple change in the construction and arrangement of the parts.

10 Having thus described my invention, I claim—

1. The combination, with a journaled shaft having an arm or handle secured thereto, and a hammer secured to said arm or handle, of means for partially rotating the shaft to lower the hammer, a spring-actuated frame, and ropes or chains secured to the frame and wrapped around and secured to the journaled shaft, substantially as set forth.

20 2. The combination, with a journaled shaft carrying an arm or handle and a hammer secured to the outer end of the arm or handle, of a spring-actuated frame, ropes or chains connecting the frame and shaft, said ropes or chains being wrapped upon the shaft, and another rope or chain wrapped one or more times around the shaft, whereby, upon pulling said rope or chain, the shaft is partially rotated, as set forth.

30 3. The combination, with a journaled shaft carrying an arm or handle and a hammer secured to said arm or handle, of a spring-actuated frame, ropes or chains secured to the frame and wrapped around and secured to the shaft, a swiveled foot-lever, and a rope or chain

connecting the foot-lever with the shaft and wrapped around the said shaft, as set forth.

4. The combination, with a journaled shaft carrying an arm or handle and a hammer secured to said arm or handle, of a spring-actuated frame, ropes or chains secured to the frame and wrapped around and secured to the shaft, a rope or chain wrapped around and secured to the shaft, and a stop, substantially as set forth.

45 5. The combination, with a journaled shaft carrying an arm or handle and a hammer secured to said arm or handle, of a spring-actuated frame, ropes or chains secured to the frame and wrapped around and secured to the shaft, a swiveled foot-lever, a rope or chain secured to the same and wrapped around and secured to the shaft, and a stop, as set forth.

6. The combination, with a journaled shaft carrying an arm having a hammer secured at its outer end, of a frame, spring-rods secured to the lower ends of the uprights composing the frame and to the supporting-base, ropes or chains secured to the frame and wrapped around and secured to the shaft, and means 55 for partially rotating the shaft to cause the hammer to be raised and lowered, as set forth.

In testimony that I claim the foregoing as my own I have hereto affixed my signature in presence of two witnesses.

MINNIS HEADEN.
